UNITED STATES PATENT OFFICE.

GEORGE A. GUENTHER, OF BUFFALO, NEW YORK, ASSIGNOR OF ONE-HALF TO GEORGE DUCHSCHERER, OF BUFFALO, NEW YORK.

HEATING APPARATUS.

Application filed January 22, 1923. Serial No. 614,150.

To all whom it may concern:

Be it known that I, GEORGE A. GUENTHER, a citizen of the United States, residing in Buffalo, in the county of Erie and State of New York, have invented new and useful Improvements in Heating Apparatus, of which the following is a specification.

This invention relates to a gas heating apparatus of the type which utilizes suction 10 for circulating the heated air through the radiator.

One of its objects is to produce a reliable and efficient heating apparatus of this character which is simple and compact in construction and economical in operation.

A further object of the invention is to provide improved means for positively shutting off the gas supply without affecting the suction supply of the apparatus.

Still further objects of the invention and features of construction will appear in the description and be particularly pointed out in the appended claims.

In the accompanying drawings: Figure 1 is a front view of the heater embodying my invention. Figure 2 is a rear view thereof. Figure 3 is a transverse vertical section on line 3—3, Fig. 1. Figure 4 is a horizontal section on line 4—4, Fig. 1. Figure 5 is an enlarged transverse vertical section on line 5—5, Fig. 1. Figures 6 and 7 are enlarged vertical longitudinal sections on the correspondingly numbered lines in Fig. 4. Figure 8 is a transverse vertical section on line 8—8, Fig. 7. Figure 9 is a rear view of the heater showing the various parts of the apparatus connected therewith.

Similar characters of reference refer to like parts throughout the several views.

In its general organization, this heating apparatus comprises a radiator having a burner or combustion box communicating therewith, suction means for drawing air through the radiator, an automatic valve for controlling the admission of gas to the burner and governed by the air suction through the radiator, and a supplementary or cut-off valve for controlling the admission of gas to the burner and operable both manually and automatically independently of the air suction.

10 indicates the radiator which is of the well known sectional type and is provided with a burner-box or combustion chamber 11 located centrally in its upper part. The

upper end of the burner-box communicates with the adjacent inner radiator sections which are connected at their lower ends by a horizontal pipe 12 to which is joined an exhaust conduit 13 communicating with an exhaust fan 13^a or other source of artificial suction. A hinged door or lid 14 having a sight opening or window 15 is applied to the front side of said burner-box for gaining access thereto when desired.

Located within the burner-box is a suitable gas burner 16, which, as shown in Figs. 3, 5 and 6, is mounted on the upper end of a substantially upright mixing tube 17 fastened to the bottom wall of said burner-box. Disposed in rear of said mixing tube is a valve body or casing 18 which is provided with a substantially L-shaped gas passage 19 whose lower end communicates with a comparatively short horizontal pipe 20 which also serves as a means for connecting said valve casing with the lower end of the mixing tube, as shown in Fig. 5. The upper end of the valve casing has a valve seat 21 with which an automatic valve 22 co-operates for shutting off or admitting gas to the burner 16. It will be noted that the upper tubular portion 23 of the valve casing 18 containing the valve seat is somewhat smaller in diameter than its lower portion and enclosing the same is a T-fitting or head 24 which is screwed to said lower portion and to which is connected a gas supply pipe 25. By this construction, an annular space 26 is formed between these parts with which the gas passage 19 and the gas supply pipe 25 communicate. The upper end of the T-fitting may be closed by a screw plug 27.

The mixing tube 17, the passage 19, and the horizontal pipe 20 constitute a substantially U-shaped gas conduit, the gas being admitted at the upper end of said passage 19 and discharged into the burner at the outlet or upper end of the mixing tube.

In addition to the main burner 16, a pilot burner 28 may be employed. As shown in Fig. 5, it has an air passage 29 leading to the atmosphere and a gas tube 30 which is connected at its lower end to the T-fitting 25. This gas tube opens directly into the annular gas-receiving space 26 so that the pilot burner is constantly supplied with gas. The gas supply pipe 25 may be provided with a shut-off cock 31.

For the purpose of regulating the flow of

gas as it enters the lower end of the mixing tube 17, a regulating valve 32 is adjustably mounted therein and co-operates with a valve seat 33 formed in the opposing end of 5 the horizontal pipe 20.

The automatic valve 22 which controls the flow of gas to the mixing tube 17 is held open by a diaphragm operated by the air suction when the heating apparatus is in 10 operation and is held tightly to its seat by its own weight and by the gas pressure when the suction is turned off or when the apparatus is inoperative. To this end, a diaphragm-body 34 is provided which is fastened by screws 35 to the bottom of the valve casing 18. Supported within this diaphragm-body which is open at its bottom, is a comparatively large diaphragm 36 whose upper side is exposed to the action of 15 suction. The suction chamber 37 formed between this diaphragm and the top of the diaphragm body is connected by a conduit 38 with the interior of the burner box 11, so that when the heating apparatus is in operation, the suction through the vacuum pipe 13, radiator 10, burner-box, and conduit causes said diaphragm to be lifted. Located 20 above this main diaphragm and operable thereby is a comparatively small supplementary diaphragm 39 which carries a depending spindle 40 arranged to bear against the upper side of said main diaphragm. The stem 41 of the valve 22 in turn bears against the upper side of the supplementary diaphragm, so that when the main diaphragm 25 is lifted by suction, the supplementary diaphragm is likewise raised, thereby lifting said valve off its seat and allowing the gas to enter the passage 19 and the mixing tube 30 17 to the burner. By this double or differential diaphragm arrangement, any difference in the gas pressure over the air or suction pressure is overcome and the automatic valve 22 is positively held in its open position during the operation of the apparatus. Furthermore, by controlling the valve 22 in 35 this manner, it is automatically opened whenever the suction device is turned on and is likewise closed whenever said device is 40 shut off.

The upper end of the mixing tube is provided with an air-intake passage 42 for mixing the proper amount of air with the gas before it reaches the burner. The 45 amount of air admitted to the mixing tube through this air-intake is regulated by a suitable shutter-valve 43 mounted on the end of a rotatable stem 44. Arranged over this air-intake and its valve and suitably 50 supported at the side of the mixing tube is a hood 45 which is provided in its lower portion with an opening 46 over which a screen 47 extends for removing the dust from the 55 ingoing air.

For the purpose of shutting off the gas at

the radiator when desired, a supplementary valve operable independently of suction and the automatic valve 22 is provided which can be controlled manually or electrically through the medium of a thermostat. This 70 cut-off or supplementary valve, as shown in Figs. 5 and 6 and designated by the numeral 48, controls a port 49 preferably located in the lower end of the mixing-tube above the regulating valve 32. The stem 50 75 of said valve is pivoted at its upper end to a pair of ears 51 formed on a horizontal rock shaft 52 mounted in the upper end of the mixing-tube. This valve closes upwardly against its seat and unless some provision was made to guard against it, said valve would always tend by its own weight to seek its open position. In order to positively and reliably hold the valve in one position or the other, one end of its actuating 80 shaft 52 has fixed transversely thereon a counterweight which preferably consists of a tube 53 closed at either end and partly filled with mercury or other heavy fluid. When this tube is tilted manually in one direction or the other, the weight of its fluid contents overbalances that of the valve and its associated parts so that said valve is positively held in a set position. As shown 85 in the drawings, this weighted-tube is located at the front side of the radiator where it can be conveniently shifted to one position or the other to effect an opening or closing of the valve.

In addition to operating the valve 48 manually through the medium of the mercury tube 53 as a handle, the same may be actuated automatically in response to temperature changes in the room in which the radiator is located. The preferred means 100 for accomplishing this result are shown in Figs. 1, 3 and 7 and consist of a solenoid magnet 54 operatively connected to the weighted tube, and a thermostat 55, both of 105 said parts being included in a battery circuit 56. The solenoid magnet is disposed in a horizontal position lengthwise of the radiator and is secured by screws 57 or other fastenings to a pair of bracket arms 58 projecting forwardly from the mixing-tube 17. 110 The movable core 59 of the solenoid is operatively connected with the tube 53 by a link 60 carried by the lower end of an arm 61 depending from the central portion of 115 said tube. By this construction and arrangement, when the temperature of the room reaches the maximum point for which the thermostat is set, the circuit 56 is closed, thus shifting the solenoid core and rocking the mercury tube in the proper direction to 120 close the mixing-tube valve 48, whereupon the gas supply to the burner is shut off and the latter goes out. When the room temperature drops below normal again the solenoid 125 core is shifted in the opposite direction and 130

the valve is opened, thereby admitting gas to the main burner, which is ignited by the pilot burner. The final movement of the solenoid core in each direction is supplemented by the mercury tube 53.

As shown in Figs. 7 and 8, the hood 45 is so constructed that its lower portion extends over and encloses the solenoid, leaving an air space 62 between the latter and said hood to permit the air, entering through the screen 47 to circulate around the solenoid before it passes through the intake 42 to the mixing-tube. By this construction, the solenoid is protected from the heat given off by the radiator and the air circulating about it keeps it cool.

In utilizing a number of these radiators, such for example, as in the heating of a home, they are all connected to a common source of suction and to the gas pipe leading from the customary gas meter. The air suction through each radiator remains constant at all time regardless of whether all the radiators are on or not. While it is necessary that the suction must be on in order to operate any or all of the radiators so as to automatically open the gas-inlet valve 22 of each of the latter, the supplementary valve 48 in the mixing tube 17 is operable independently of the suction, whereby each radiator can be separately controlled without in any way affecting the suction pressure in the line or disturbing the position of said gas-inlet valve.

25 I claim as my invention:

1. A heating apparatus, comprising a combustion chamber, a burner therefor, a suction device communicating with said combustion chamber, a valve having a stem controlling the admission of fuel to the burner, and means for automatically opening said valve upon the operation of the suction device, said means comprising a diaphragm chamber in communication with the combustion chamber, and diaphragms of different areas located in said chamber and arranged so that the movement of one affects the movement of the other, the larger diaphragm being exposed to the atmosphere and the 50 valve stem engaging the smaller diaphragm.

2. A heating apparatus, comprising a combustion chamber, a burner therefor, a suction device communicating with the combustion chamber, a gas-conduit having its outlet end opening into said burner, an automatic valve located in the inlet end of said conduit and controlling the admission of fuel thereto, said valve being open when said suction device is operative, a supple-

mentary valve having a stem located in 60 said conduit beyond said automatic valve for cutting off at will the fuel supply to the burner, a rock shaft to which said valve stem is connected, and a counterweighted element applied to said shaft for holding 65 said valve in a set position.

3. A heating apparatus, comprising a combustion chamber, a burner therefor, a suction device communicating with the combustion chamber, an automatic valve for 70 controlling the admission of fuel to the burner, means operable by the suction for opening said automatic valve, a gas cut-off valve located between the latter and the burner, a rock shaft operatively connected 75 to said cut-off valve to actuate it, an arm applied to said rock shaft, and thermostatic mechanism including a solenoid having its core operatively connected to said arm.

4. A heating apparatus, comprising a 80 combustion chamber, a burner therefor, a suction device communicating with the combustion chamber, a gas-conduit having its outlet end opening into said burner, a valve at the inlet end of said conduit for controlling the admission of fuel thereto, said valve being open when said suction device is operative, a cut-off valve located in said conduit beyond said automatic valve, thermostatic mechanism including a solenoid operatively connected to said cut-off valve, 85 said conduit having an air-intake arranged between the cut-off valve and the burner, and a hood enclosing said air-intake and said solenoid and having an opening there- 90 in communicating with the atmosphere.

5. A heating apparatus, comprising a combustion chamber, a burner therefor, a suction device communicating with the combustion chamber, a valve casing containing 100 a gas-passage having a valve-seat at one end, a mixing-tube for the burner communicating with the other end of said passage, a valve in said casing for controlling the fuel supply, means to effect the seating of the valve 105 upon the stopping of the suction device and the unseating of the valve upon the starting of the latter, a normally open cut-off valve arranged in said mixing-tube, the latter having an air-intake passage above said cut-off 110 valve, a thermally-controlled solenoid applied to said mixing-tube and having its core operatively connected to the cut-off valve, and a hood open at its bottom arranged to extend over the solenoid and the 115 air-intake passage.

GEORGE A. GUENTHER.
